UNITED STATES PATENT OFFICE.

AARON SILKMAN AND HARRY SEXTON, OF NEW YORK, N. Y.

HORSESHOE.

SPECIFICATION forming part of Letters Patent No. 617,789, dated January 17, 1899.

Application filed May 27, 1896. Serial No. 593,302. (No model.)

To all whom it may concern:

Be it known that we, AARON SILKMAN and HARRY SEXTON, citizens of the United States, and residents of New York, in the county of New York and State of New York, have invented certain new and useful Improvements in Horseshoes, of which the following is a specification, reference being had to the accompanying drawings, forming a part thereof, in which similar numerals of reference indicate corresponding parts.

This invention relates to horseshoes; and the object thereof is to provide a shoe of this class with detachable calks, the special object being to provide calks which can be readily removed when worn down to or nearly to the shanks thereof and to replace the same with new calks without removing the shoe from the hoof.

The invention is fully disclosed in the following specification, of which the accompanying drawings form a part, in which—

Figure 1 is a bottom plan view of a horseshoe made according to our invention, one of the heel-calks being removed. Fig. 2 is a side view thereof. Fig. 3 is a view of one of the detachable calks, and Fig. 4 is a view of a sharpened calk.

In the drawings forming a part of this specification the separate parts of our improvements are designated by numerals of reference, and we have shown at 5 a horseshoe provided with a groove 6, with which communicate nail-holes 7, by which the shoe may be secured to the hoof of a horse. We also provide detachable calks 8, which are provided with screw-threaded shanks 9, the said calks 8 being adapted to serve as heel-calks, and the ends of the shoe 5 are provided with screw-threaded openings 10, adapted to receive the shanks 9 of the calks 8, and said shanks are provided centrally with a bore or passage which extends therethrough and into the calk to a point adjacent to the end thereof, as clearly shown in dotted lines in Figs. 2, 3, and 4, and the said holes are angular in form in cross-section, as shown in dotted lines in Fig. 1, the object of which will be hereinafter more fully explained.

The body portions of the toes 8 are preferably angular in form in cross-section and made to conform to the sides of the shoe when

secured in place, and the shanks 9 thereof may be turned into place by means of an angular key (not shown) the construction of 55 which will be readily understood, or the same may be operated by means of a wrench upon the calks, as will be readily understood.

Instead of using a calk with a flat end we may use a sharpened calk, as shown at 8' in 60 Fig. 4, the operation of securing the same in place being the same as described above.

We also provide a toe-calk which consists of two separate parts 12 and 13, each of said parts being oblong in form and each being 65 beveled on one end, as shown at 14, and each of said parts is provided with a screw-threaded shank 15, and the toe of the shoe is provided with screw-threaded openings 16, adapted to receive said shanks, and each of said parts 12 70 and 13 is provided with angular bores or passages 11, which extend through the shanks thereof into the wearing part, as clearly shown in dotted lines, and when connecting the separate parts with the shoe the part 12 is first 75 screwed far enough in, so that only a quarter-turn is necessary to screw it entirely home, when the part 13 is screwed into position, and in order to facilitate this operation the inner end of the part 13 is cut away, as shown at 80 16', and when the part 13 is entirely home the part 12 is given the quarter-turn and is also home, as will be readily understood.

As described above, the bores or passages 11 extend through the shanks of the calks 8 and 85 parts 12 and 13 into the wearing part and to a point adjacent to the end thereof, so that when the said calks or parts 12 and 13 are worn down in use the said bores or passages will extend entirely through the remaining 90 part, thereby communicating with the surface, and by inserting a key with a shank corresponding in shape to the said bore or passage the said calks may be removed from the shoe and new ones may be secured in place, the latter operation being performed with a wrench, thereby avoiding the necessity of removing the shoe from the hoof.

The advantage of this construction will be readily understood when it is remembered that the calks are generally worn down so close to the shoe before they are removed that it would be impossible to grip the same with a wrench, and if the means for disengaging

the same consisted of external grooves or recesses the edges of the same would also be liable to be worn away, so that a key would not effectively engage them to operate the shanks, while in this construction the bores or passages are protected from wear and the calks can be removed at any time without any difficulty, no difference how much the calks are worn away.

10 Our improvement is well adapted to accomplish the result for which it is intended, and by means thereof a smooth shoe may be quickly and easily converted into a sharpened one, and it will thus be seen that we accomplish the object of our invention in a simple and efficient manner and by a construction which is comparatively inexpensive, and we reserve the right to make any changes which fairly come within the scope of our invention.

15 Having fully described our invention, what we claim, and desire to secure by Letters Patent, is—

1. A horseshoe-calk consisting of a body and a screw-threaded shank, said body and shank provided with a passage with which a tool may be engaged from below the shoe for unscrewing the shank when the calk is worn and without removing the shoe from the hoof of the horse.

2. A horseshoe-calk consisting of a body and a screw-threaded shank, said shank and body provided with a vertical keyway of the same form throughout its length, with which a key may be engaged from below the shoe when the calk is worn and without removing the shoe from the hoof of the horse, substantially as described.

3. A horseshoe provided with a detachable calk having a screw-threaded shank which is provided with a bore or passage which is normally closed when the shoe is in position and

open when a portion of the wearing part of said calk is worn away, whereby the said calk may be removed without removing the shoe from the hoof.

45

4. A horseshoe provided with a detachable calk which is provided with a screw-threaded shank having a central bore or passage extending therethrough and into the wearing portion of the said calk, whereby the said bore or passage is in communication with the outer end of said calk when partially worn away, for the purpose set forth.

5. A horseshoe provided with a detachable calk which is provided with a screw-threaded shank, the said shank being provided with a central bore or passage which extends therethrough and into the said calk to a point adjacent to the outer end thereof, whereby the said bore or passage is placed in communication with the outer surface of said calk by the wearing away of the same, and being angular in form in cross-section, substantially as and for the purpose described.

6. A horseshoe provided with a detachable calk which is provided with a screw-threaded shank, the said shank being provided with a central bore or passage which extends therethrough and into the wearing-surface of the said calk to a point adjacent to the outer end thereof, and being angular and prismatic in form throughout its entire length, substantially as and for the purpose described.

In testimony that we claim the foregoing as our invention we have signed our names, in presence of the subscribing witnesses, this 25th day of May, 1896.

AARON SILKMAN.
HARRY SEXTON.
